US00D960207S

(12) United States Design Patent (10) Patent No.: US D960,207 S
(45) Date of Patent: * Aug. 9, 2022

(54) REFRIGERATOR

(71) Applicant: LG ELECTRONICS INC., Seoul
(KR)

(72) Inventors: Sookyung Kang, Seoul (KR);
Kyukwan Choi, Seoul (KR);
Myungshik Kim, Seoul (KR);
Hyoungwon Roh, Seoul (KR); Junyi Heo, Seoul (KR)

(73) Assignee: LG ELECTRONICS INC., Seoul
(KR)

() Term: 15 Years

(21) Appl. No.: 29/776,906

(22) Filed: Apr. 1, 2021

(30) Foreign Application Priority Data

Oct. 12, 2020 (KR) 30-2020-0048742

(51) LOC (13) Cl. 15-07

(52) U.S. Cl. ..... USPC D15/89

(58) Field of Classification Search

(57) CLAIM

The ornamental design for a refrigerator, as shown and described.

DESCRIPTION

FIG. 1 is a front perspective view of the refrigerator showing our new design;

FIG. 2 is a front view thereof;

FIG. 3 is a back view thereof;

FIG. 4 is a left side view thereof;

FIG. 5 is a right side view thereof;

FIG. 6 is a top plan view thereof;

FIG. 7 is a bottom plan view thereof;

FIG. 8 is a bottom perspective view thereof; and,

FIG. 9 is an enlarged view of a portion of FIG. 8.

The broken lines depict portions of the refrigerator that form no part of the claimed design.

The dash-dot broken lines define the bounds of the claimed design and form no part thereof.

1 Claim, 9 Drawing Sheets
